UNITED STATES PATENT OFFICE.

GLENN F. COUCH, OF ROCHESTER, NEW YORK, ASSIGNOR TO THE SYMINGTON COMPANY, OF NEW YORK, N. Y., A CORPORATION OF MARYLAND.

ARTICULATED JOURNAL STOP.

Application filed January 21, 1925. Serial No. 3,868.

The invention relates to journal boxes and has particular reference to stop means for taking up any end thrust of the journal and preventing distortion of the box as the result of longitudinal movement of the journal with respect thereto.

It is well known that truck side frames move out of alignment both horizontally and vertically when rounding curves, passing crossovers, etc., under ordinary service conditions. This movement of the side frames causes the journals to move longitudinally and to tilt vertically as well as laterally with respect to the journal boxes. The general arrangement of the journal, bearing brass and wedge block in the journal box is such that endwise movement of the journal toward the open end of the box brings an excessive strain upon the retaining lug on the box top or roof, so that breakage often results. It is with these facts in view that I have designed the present invention which contemplates the provision of a stop carried by the opposite sides of the box and so positioned as to be normally out of engagement with the journal but adapted to be engaged thereby for taking up the end thrust and transmitting the strain to the sides of the box instead of to the stop lug on the top or roof.

Another object of the invention is to provide a journal stop embodying a thrust receiving structure located in position to be engaged by the end of the journal in the event of longitudinal movement thereof, this structure including elements having a gimbal joint or connection whereby the thrust receiving element may accommodate itself to the end of the journal and bear flatly thereagainst regardless of whether the journal be tilted laterally or vertically with respect to the box.

A further object of the invention is to provide a journal stop formed of or embodying detachably connected sections held normally in assembled relation by a supporting element removably mounted within the journal box, the entire device constituting an assembly and being insertible in place and removable as such, the parts being incapable of separation while in mounted and operative position.

Still another object of the invention is the provision of a stop device of this character which may be removed or replaced through the open end of the box without interference with any of the parts thereof.

Another object of the invention is to pro-

vide an articulated journal stop in which the relatively movable parts are provided with comparatively large coaxial bearing surfaces so that they are capable of withstanding great pressure without danger of breakage, the parts being so mounted as to provide for universal movement of the stop face within the necessary or desirable range.

The invention further contemplates the provision of a device of this character which involves few parts preferably formed as castings and which may consequently be produced at small expense.

To these and other ends the invention comprises the various elements and combinations of elements to be hereinafter described and set forth in the claims hereunto appended.

In the drawings:

Figure 1 is a vertical sectional view through a journal box taken outwardly of the journal and looking there-toward, this view illustrating the stop in place, a portion of the stop being in elevation and a portion in section.

Figure 2 is a vertical section taken longitudinally of the journal on substantially the line 2—2 of Figure 1.

Figure 3 is a fragmentary section through the journal box showing a plan view of the stop.

Figure 4 is a horizontal section through the stop taken axially of the mounting and supporting element, this element being in elevation.

Figure 5 is a perspective view showing the two elements of the stop separated.

Figure 6 is a cross-section on the line 6—6 of Figure 4.

Figure 7 is a detail section on the line 7—7 of Figure 3.

Throughout the specification and drawings like parts are designated by like reference characters.

Referring more particularly to the drawings, the letter A designates a portion of a journal box including a roof B from which depends a lug C which, under ordinary circumstances, is engaged by certain elements within the journal box and is subject to great strain in the event of longitudinal outward movement of the journal D. In carrying out the present invention I provide a stop device, indicated generally at 1, which includes a plurality of sections so mounted as to take up the thrust in the event of lengthwise move-

ment of the journal and prevent strain being transmitted to the lug C with probable damage to the roof.

In the present instance the stop device 1 is shown as including a supporting element or pintle 2, the axis of which is preferably substantially horizontal, a rotatable member 3 mounted thereon, and a rockable thrust receiving member 4. While the specific construction of these members or sections may be varied, I have found it convenient to construct or form the member 3 as a casting of elongated form and of substantially cylindrical shape and provided with a bore 5 through which passes the supporting element 2 which is preferably of cylindrical pin-like formation. Intermediate its ends the member 3 is provided with an open portion 6 for a purpose to be described, and the upper and lower edges of said member are preferably provided with stiffening flanges or webs 7. The end portions 8 of the member 3 constitute bearings which engage upon the supporting element or pin 2 while the intermediate portion is cored out or otherwise formed to provide a chamber or space 9.

The member 4 as shown includes a relatively large wear plate portion 10 carrying a U-shaped attaching portion 11 which may be integral therewith and which is received within the space or chamber 9 when the stop is assembled, this U-shaped portion 11 also accommodating or embracing the supporting element or pin 2 which passes therethrough and which serves as the means for connecting the members 3 and 4. The plate portion 10 may be reinforced by providing the same with a pair of outstanding flanges 12 braced by webs 13. The outer surfaces of these flanges 12 are preferably arcuate to provide trunnion portions and conform to the curvature of the corresponding bearing surfaces 14 at the upper and lower edges of the member 3. Within the U-shaped attaching portion 11, the plate portion 10 may be provided with a vertical ridge 15 which will serve as a fulcrum engaging the pin 2 and upon which the plate portion 10 may rock so as to be capable of lateral tilting. For this reason it is intended that the U-shaped attaching portion 11 fit loosely upon the pin 2 and that the inner surface of its bight portion be beveled off outwardly, as shown at 16, so as not to interfere with the lateral tilting movement. During any such tilting the flanges 12 will bear against the concaved bearing surfaces 14 of the member 3. From the foregoing description it will be seen that the stop plate is so mounted as to have universal movement, said mounting constituting a gimbal joint.

For connecting the stop assembly to and within the journal box, a convenient arrangement is to provide inwardly extending bosses 17 on the inner faces of the side walls

of the box A, these bosses being formed with vertically extending slots 18 and 19 which extend clear to the top. The slots 19 are of greater width than the slots 18 so as to accommodate the ends of the supporting element or pin 2 which has its extremities cut away at opposite sides or otherwise formed to define narrow extensions 20 located within the slots 18. The slots 19 are of slightly greater width than the diameter of the pin 2 while the slots 18 are of considerably larger size than the thickness of the extensions 20. At one edge of each slot 18 may be provided a slight overhang 21 which defines a constricted entrance 22 to the slot, however, of sufficient width to permit ready passage of the extension 20. By this arrangement it will be noted that when the pin 2 is in place accidental vertical displacement thereof will be prevented owing to the fact that tendency to move upwardly will be checked by engagement of the extensions 20 with the overhanging shoulders or ledges 21 while at the same time the assembly may be removed by pulling it bodily upwardly and moving it toward the journal so that the extensions 20 will clear the shoulders or ledges 21.

It is unnecessary for the member 3 to have a wide degree of rotative movement and for this reason I have shown it as provided at its ends with extensions 23 which project somewhat into the slots 19. However, the width of these extensions is less than the width of the slots so that the member 3 may rotate to a sufficient extent to permit the plate portion 10 of the member 4 to accommodate itself to the end of the journal in case the latter moves into engagement therewith at such a time that its axis is not in horizontal position. The location of these extensions within the slots will, however, operate to prevent the members 3 and 4 from turning to such an extent as to drop out of place. The lateral turning movement of the member 4 so that the plate portion 10 thereof may conform to the end of the journal in case the latter engages thereagainst while its axis is tilted into a position other than its normal transverse position has been described.

From the foregoing description and a study of the drawings it will be apparent that I have thus provided a simply constructed and easily installed or removed journal stop formed of articulated sections and one in which the wear and thrust receiving member may accommodate itself at all times to the position of the journal in case the latter engages thereagainst, the advantage being that a flat bearing surface will be presented for taking up the thrust and transmitting it to the sides of the box, consequently avoiding the bringing of any undue strain upon other and weaker portions of the structure. In case of breakage of any part or wearing out of the journal engaging member it is evident

that the entire assembly is easily capable of bodily removal and subsequent separation so that a new part may be substituted and the assembly reinstalled, all of which operations 5 may be accomplished in a simple and expeditious manner and without disturbing the journal box or its connections.

While I have shown and described the preferred embodiment of my invention, it is to 10 be understood that I reserve the right to make all such changes in the form, construction and arrangement of parts as will not depart from the spirit of the invention or the scope of the subjoined claims.

15 Having now described my invention, what I claim as new and desire to secure by Letters Patent is:

1. The combination with a journal box and journal therein, of an articulated stop structure formed as an assembly bodily removably mounted within the box and including a thrust receiving member positioned outwardly of the journal and adapted to be engaged by the end thereof upon the occurrence of 25 longitudinal movement, and a mounting for the thrust receiving member permitting universal movement thereof, said mounting comprising a pintle member about which the thrust receiving member pivots up and down 30 and a bearing member supported on said pintle member and on which the thrust receiving member oscillates laterally.

2. In combination with a journal box and journal therein, a thrust receiving member located outwardly of the end of the journal and normally spaced therefrom, said thrust receiving member being engageable by the end of the journal upon longitudinal movement thereof and mounted for pivoting about 40 a plurality of angularly disposed axes to accommodate itself to lateral and vertical tilting of the journal.

3. The combination with a journal box and a journal therein, of an articulated stop assembly comprising a thrust receiving member and a bearing member upon which it pivots laterally, and supporting means for holding the assembly within the box and permitting substantially vertical pivoting thereof, the 50 supporting means normally holding the thrust receiving and bearing members in assembled relation and being removable to permit separation of the parts of the assembly upon bodily removal of the assembly from the 55 box.

4. The combination with a journal box and a journal therein, of an articulated stop including detachably connected bearing and thrust receiving members, said members being 60 provided with coacting bearing surfaces permitting transverse tilting of the latter, and pivotal supporting means for said stop permitting vertical angling thereof, whereby universal angling of the thrust receiving element is permitted.

5. The combination with a journal box and a journal therein, of an articulated stop including detachably connected members, one member being formed as a journal thrust receiving element, said members being provided with coacting bearing surfaces permitting transverse angling therebetween, said surfaces being adapted to remain constantly in engagement during swiveling movement of the thrust receiving element, and means 70 pivotally connecting said members to the box about an axis disposed at an angle to the axis of the stop bearing surfaces.

6. In combination with a journal box and a journal therein, of an articulated stop formed 80 as an assembly including a supporting element, a bearing member rotatably mounted thereon, and a thrust receiving member positioned by said supporting element outwardly 85 of the end of the journal and adapted to tilt laterally with respect to the bearing member, said last named member being pivotally movable vertically with respect to the supporting element.

7. In combination with a journal box and a journal therein, of an articulated stop formed as an assembly including a supporting element, a bearing member rotatably mounted thereon, and a thrust receiving member also mounted on the supporting element 90 and positioned outwardly of the end of the journal, and said last named member being pivotally movable with respect to the supporting element in a substantially vertical direction, said bearing member and said thrust receiving member being provided with curved coacting bearing surfaces remaining 95 constantly in engagement and permitting transverse oscillation therebetween.

8. In combination with a journal box and a journal therein, of an articulated stop formed as an assembly including a supporting element, a bearing member rotatably mounted thereon, a thrust receiving member positioned on the supporting element, and 100 adapted to angle transversely with respect to said bearing member, and positioned outwardly of the end of the journal, and said last named member being pivotally movable with respect to the supporting element about a substantially horizontal axis, and means on opposite sides of the box for supporting said 110 supporting element.

9. In combination with a journal box and a journal therein, of an articulated stop formed as an assembly including a supporting element, a bearing member rotatably mounted thereon, a thrust receiving member positioned outwardly of the end of the journal, and said last named member having 120 trunnion portions engaging the bearing member and being pivotally movable with respect to the supporting element about an axis transverse to that of the trunnion portions whereby universal motion thereof is permitted, and 125 130

means on opposite sides of the box for supporting said supporting element, said bearing member having means engageable with said last named means for limiting rotatable movement.

10. In combination with a journal box and a journal therein, of an articulated stop formed as an assembly including a supporting element, a member rotatably mounted thereon and formed with concave bearing portions, a thrust receiving member held in place on said supporting element by means of said first named member and formed with portions rotatably mounted in said bearing portions and positioned outwardly of the end of the journal, said thrust receiving member being pivotally movable with respect to the supporting element about an axis transverse to that of the bearing portions on said first named member, and socket members located on opposite sides of the box removably supporting the supporting element of the assembly.

11. The combination with a journal box and journal therein, of an articulated stop assembly including a relatively stationary supporting element, a bearing member mounted thereon for limited rotative movement, and a thrust receiving member rockably mounted upon said supporting element and having trunnion portions engaging said bearing member and movable thereon about a different axis.

12. The combination with a journal box and journal therein, of an articulated stop assembly including a relatively stationary supporting member, a member mounted thereon for limited rotative movement; and a thrust receiving member rockably mounted about a different axis upon said supporting element and having portions bearing against said first named member, said supporting element acting to hold said first named member and thrust receiving member in assembled relation.

13. The combination with a journal box and journal therein, of an articulated stop assembly including a relatively stationary supporting member, a member mounted thereon for limited rotative movement, and a thrust receiving member rockably mounted about another axis upon said supporting element and having portions bearing against said first named member, said supporting element acting to hold said first named member and thrust receiving member in assembled relation and being capable of withdrawal upon removal of the assembly from the box whereby to permit separation of the first named member and the thrust receiving member.

14. The combination with a journal box and journal therein, of a stop assembly including a relatively stationary supporting element, a member having bearing portions surrounding said supporting element and having arcuate bearing surfaces, and a thrust receiving member having a portion surrounding said supporting element and rockably engaged therewith, said thrust receiving member having arcuate surfaces bearing against said first-named arcuate surfaces and movable thereon about an axis different from that of the bearing portions of the first named member.

15. In combination with a journal box and journal therein, a stop assembly comprising a pintle member supported from the opposite sides of the journal box, a bearing member mounted thereon and adapted for upward and downward swinging with respect thereto and a thrust receiving member mounted on the pintle member and formed with trunnion portions for transverse rocking movement with respect to the bearing member and adapted for engagement with the adjacent end of the journal and receiving end thrust therefrom.

In testimony whereof I affix my signature.

GLENN F. COUCH.
